UNITED STATES PATENT OFFICE.

ALPHEUS A. NOBLE, OF WATERBOROUGH, MAINE.

TRACK-RAISER.

SPECIFICATION forming part of Letters Patent No. 634,699, dated October 10, 1899.

Application filed March 16, 1899. Serial No. 709,305. (No model.)

To all whom it may concern:

Be it known that I, ALPHEUS A. NOBLE, a citizen of the United States, residing at South Waterborough, in the county of York and State of Maine, have invented certain new and useful Improvements in Track-Raisers; and I do hereby declare the following to be a full, clear, and exact description of the invention, such as will enable others skilled in the art to which it appertains to make and use the same.

This invention relates to certain new and useful improvements in track-raisers, and has for its object to construct a device whereby the rails of a railroad-track are raised and held in a raised position while being leveled.

A further object of my invention is to construct a device whereby one man can accomplish the same amount of work as a number of men and do it better.

In describing my invention in detail reference is had to the accompanying drawings, forming a part of this specification, wherein like figures of reference indicate similar parts throughout the several views, in which—

Figure 1 is a side elevation of my improved track-raiser with parts broken away. Fig. 2 is a rear end elevation of the same. Fig. 3 is a front end elevation of the same, the frame being in section.

Referring to the drawings, 1 designates a hollow frame mounted on wheels 2 of the ordinary car-wheel type. Secured to the frame 1 by means of L-shaped irons 3 is a frame 4, which projects above and below the same. Said frame 4 has secured at the top a brace 5. The opposite end of said brace 5 is secured to the rear end of the frame 1. Secured in said frame 4 at a point predetermined from the bottom thereof are eyebolts 6. Engaging said eyebolts 6 are rods 7, said rods 7 having the ends bent at substantially right angles and engaging an adjustable frame 8. Said frame has secured to its upper end arms 9, in which is secured a shaft 10. Secured to one end of said shaft 10 and outside of the arms 9 is a ratchet-wheel 11. Secured to the upper end of the frame 4 and engaging the teeth of the ratchet-wheel 11 is a dog 12. Secured in the frame 8 and passing through the same from the opposite side from the rods 7 are rods 14, said rods being substantially the same shape,

but somewhat longer than the rods 7. Engaging said rods 14 and secured in frame 15 are eyebolts 16. Pivotedly secured to the frame 15 at 17 are dogs 18. Said dogs are provided with inwardly-extending arms 19, the ends of which project beyond a central point of the apparatus. Fulcrumed to one side of the frame 15 is a lever 20, to one end of which is secured a link 21. The lower end of said link 21 engages the arms of the dogs 18. The handle of said lever 20 is held in an elevated position by a dog 22. Secured to the dogs 18 at 23 is a chain 24, the opposite end of which is secured to the shaft 10. Fulcrumed to the frame 4 and on the rear side thereof is a lever 25, the opposite end of which is pivotally secured to a link 26. The opposite end of said link 26 is secured to the frame 8. The handle of said lever 25 is held in the depressed position by the dog 27.

Operation: Supposing all parts to be in the position shown in Fig. 2, the machine is moved along the track to the point where the track is to be raised to a certain level, the dog 27 is disengaged from the lever 25, and the frame is lowered until the bottom rests on one of the cross-ties or on the ground between the cross-ties. The dog 12 is then released from the ratchet-wheel 11 and the chains 24 unwound from the shaft 10 until the dogs 18 reach a point below the lower face of the rail. The lever 20 is then elevated until the engaging face of the dogs 18 are horizontal. The lever 20 is then secured in that position by the dog 22. To raise the track, the nails are withdrawn from the cross-ties and the chains are wound on the shaft 10 by the levers 28, which raises the frame 15 and dogs 18, carrying the rails with it, when the necessary repairs can be made.

By the construction shown and described one man can accomplish more work than a number of men, and at the same time do the work in less time.

It will be noted that various changes may be made in the details of construction without departing from the spirit of my invention.

Having thus described my invention, what I claim, and desire to secure by Letters Patent, is—

1. In an apparatus of the class described, a horizontal frame, a vertical frame, a sliding

frame carried by said vertical frame, a secondary sliding frame carried by said first-named sliding frame, and means carried by the sliding frame whereby the track is raised, 5 substantially as shown and described.

2. A track-raiser consisting of a horizontal frame, a frame secured vertically to said horizontal frame, a sliding frame carried by said vertical frame, a sliding frame carried by said 10 first-named sliding frame, dogs fulcrumed to the lower end of said last-named sliding frame, and means carried by said first-named sliding frame whereby the second sliding frame and dogs are raised to elevate the track, substantially as shown and described. 15

3. A track-raiser consisting of a horizontal frame, a vertical frame 4 secured to said horizontal frame, a sliding frame 8 carried by said

vertical frame 4, arms secured to the upper end of said frame 8, a shaft journaled in said arms, a sliding frame 15 carried by said frame 8, dogs fulcrumed to the lower end of said frame 15, a lever to hold said dogs in an engaging position, chains secured to said dogs and to the shaft whereby the frame 15 and 20 the track are elevated, and means carried by the frame 4 whereby the frame 8 is raised and lowered, substantially as shown and described. 25

In testimony whereof I affix my signature 30 in presence of two witnesses.

ALPHEUS A. NOBLE.
